PATTERN CONTROL ARRANGEMENT FOR
CIRCULAR KNITTING MACHINES

Erich Ribler, Kenzingen, Germany, assignor to Franz
Morat K.G., Eisenbach, Black Forest, Germany
Filed Apr. 20, 1964, Ser. No. 361,310
Claims priority, application Germany, Apr. 20, 1963,
M 56,550
20 Claims. (Cl. 66—50)

The present invention relates to a pattern control arrangement for a knitting machine, and more particularly to a program controlled apparatus provided at one or several knitting stations of a circular knitting machine for placing selected needle-influencing elements in an operative position for the purpose of shifting correlated needles to the knit position.

Other non-selected needles are not shifted, or are shifted, for example, to the tuck position so that a predetermined pattern is knitted by the needles of the machine.

In one known construction, a pattern wheel is provided at each knitting station and mounted for rotation about an axis inclined at a small acute angle to the axis of the knitting machine so that needle-influencing elements, commonly termed "jacks" raise the cylinder needles while moving in a plane slanted to the direction of movement of the cylinder needles.

In other known constructions, needle influencing elements or "jacks" are mounted in the pattern wheels for movement in axial direction and abut the knitting needles and shift the same directly to the advanced position when moving to the operative position.

Other known constructions provide needle-influencing elements in the grooves of the needle cylinder in which the needles are mounted, and the movement of the needle-influencing elements to an operative position effects shifting of selected needles.

Pattern wheels with needle-influencing elements moving in the direction of the needles can also be provided for the dial of a circular knitting machine for operating the dial needles in accordance with a predetermined pattern.

It is known to effect the movement of the needle-influencing elements to an operative position by electromagnetic means which are energized and deenergized in accordance with a predetermined pattern and act on intermediate resilient members which cooperate with a needle-influencing element to shift the same. The resilient members are engaged by a cam after a slight displacement, and the cam moves the resilient members such a distance that the respective needle-influencing elements are shifted to the operative position. Pattern wheels of this type are disclosed in our U.S. Patent 3,079,775.

It is one object of the invention to improve known program controlled pattern wheels, and to provide a pattern wheel which can be operated at very high speed and effects very rapid and reliable shifting of the needle-influencing elements to the operative position in which they are adapted to influence the needle movement.

Another object of the invention is to provide a pattern wheel in which program controlled electro-magnetic means select or reject the needle-influencing elements.

It is the principal object of the invention to provide a pattern control arrangement in which the movement of needle-influencing elements to an operative position is rapidly accomplished by stored energy.

A related object of the invention is to tension a spring acting on each needle-influencing element before the respective element arrives at a select station, and to release the spring at the selecting station so that the movement

2

of the element toward the operative position is accomplished by the released spring force.

Another object of the invention is to lock each spring-loaded element before the same arrives at a selecting station, and to unlock or release selected elements at the selecting station for movement toward the operative position.

Another object of the invention is to provide a pattern control arrangement in which selected locked spring-loaded elements are unlocked and released at a selecting station by electromagnetic means which are energized and de-energized in accordance with a predetermined pattern.

With these objects in view, the present invention relates

15 to a pattern control arrangement for a knitting machine, preferably a circular knitting machine having a cylinder with cylinder needles, and a dial with dial needles. One embodiment comprises rotary carrier means, which may be part of a pattern wheel or part of the knitting cylinder of the machine; a set of needle-influencing elements supported on the carrier means for rotation therewith past at least one selecting station, and for movement thereon between an inoperative position, and an operative position adapted to displace a correlated needle either after 20 turning to an operating station, or directly by moving in the same direction as the needle; biasing means, preferably a set of independent springs, biasing the needle-influencing elements to move toward the operative position; locking means, preferably a set of locking springs respectively cooperating with the needle-influencing elements for locking non-selected elements in the inoperative position, and for releasing selected elements for movement toward the operative position; and control means, preferably a program controlled electromagnetic means located at the selecting station for moving the locking means between the releasing and locking position in accordance with the predetermined program causing energization and de-energization of the electromagnetic means.

40 Cam means are provided on the stationary support of the carrier means for moving the needle-influencing elements to the inoperative position before each element arrives at the selecting station so that the respective locking spring can lock the element in the inoperative position.

In one embodiment of the invention, a stationary cam moves the locking springs to the releasing position before the selecting station where the electromagnetic means hold locking springs cooperating with selected needle-influencing elements in the releasing position but permit 45 the locking springs of non-selected elements to remain in the locking position holding the respective needle-influencing element in the inoperative position while passing through the selecting station.

While the operation of the locking springs by electromagnetic means is preferred, mechanical means or fluid operated means may be provided at the selecting station for operating the locking means. However, in accordance with the invention the movement of the needle-influencing elements toward the operative position is accomplished 50 by the energy stored in biasing means before each needle-influencing element arrives at the selecting station.

In order to achieve a very rapid selection, the stored force of the biasing means is used for moving the respective needle-influencing element to an intermediate position only, and a stationary cam effects movement of needle-influencing elements from the intermediate position, to the operative position, which is particularly advantageous if the needle-influencing elements shift correlated needles directly during movement from the intermediate position to the operative position so that the biasing means do not produce the force required for shifting the needles.

In another embodiment of the invention in which the needles are shifted by needle-influencing elements in the operative position due to the fact that the axis of the pattern wheel is inclined to the axis of the needle cylinder, the stored force of the biasing means is advantageously used for moving the needle-influencing elements all the way to the operative position.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a fragmentary schematic side view, and FIG. 1a is a fragmentary schematic front view illustrating a circular knitting machine with a pattern wheel arrangement to which the embodiment of the invention shown in FIGS. 5 to 7 is applied;

FIG. 2 is a fragmentary schematic side view illustrating a circular knitting machine with a pattern wheel arrangement to which the embodiment of the invention illustrated in FIG. 10 is advantageously applied;

FIG. 3 is a fragmentary schematic side view of a circular knitting machine provided with a pattern control arrangement to which the embodiment illustrated in FIGS. 8 and 9 is advantageously applied;

FIG. 4 is a fragmentary schematic sectional view of a circular knitting machine provided with a pattern control arrangement according to the invention;

FIG. 5 is an axial sectional view illustrating a pattern wheel according to one embodiment of the invention;

FIG. 6 is a fragmentary developed sectional view taken on line VI—VI in FIG. 5;

FIG. 7 is a fragmentary developed plan view taken on line VII in FIG. 5;

FIG. 8 comprises a series of fragmentary axial sectional views 8A, 8B, 8C, 8D, 8E taken in angularly spaced radial planes passing through the axis of the needle cylinder of a circular knitting machine constructed in accordance with another embodiment of the invention;

FIG. 9 is a fragmentary developed view taken in the direction of the arrow 9 in FIG. 8 and illustrating the shape of the cams on the cam cylinder of the machine; and

FIG. 10 is an axial sectional view illustrating a pattern wheel according to a further embodiment of the invention.

Referring now to the drawings, FIGS. 1 and 1a, as well as FIG. 5, illustrate a circular knitting machine with a needle cylinder 3 turnable about a vertical axis Y—Y and having axially extending grooves in which cylinder needles 2 are guided for vertical movement. At each knitting station around the needle cylinder, a pattern wheel is mounted for turning movement about an axis X—X which is inclined at an acute angle to the axis of the needle cylinder, as best seen in FIG. 1a, so that radially shiftable needle-influencing elements 1 move upward in a slanted plane during rotation of the pattern wheel whereby elements 1 in operative positions located under butts 2a of associated needles 2, raise the respective needles to the knit position, whereas radially retracted elements 1 will not engage butts 2a, and consequently be inoperative to raise the needles. A force P urges the needle influencing elements 1 toward the operative position, as will now be described with reference to FIGS. 5 to 7.

A support includes a fixed axle 6 whose axis X is inclined to the axis of the needle cylinder and to the needles 2, as explained with reference to FIG. 1a. A carrier means includes a hub 8 turnable about axle 6, a carrier member 7 fixed to hub portion 8, a lower plate 12 secured by screws 12a to carrier member 7, and two upper annular plate members 10 and 10a secured by screws 10b to carrier member 7.

Carrier member 7 has a set of radially extending grooves in which needle-influencing elements or "jacks" 1 are mounted for radial movement. Carrier member 7 has projecting teeth 7' which are arranged alternating with and staggered to the needle-influencing element 1 and mesh with butts, not shown, of cylinder needles 2 so that the carrier with the needle-influencing elements 1 rotates in synchronism with the needle cylinder. A locking spring 9 is correlated with each needle-influencing element 1, each locking spring 9 registering in a radial plane with the corresponding needle-influencing element 1. The ends 9a of locking springs 9 are clamped between the annular plates 10a and 10, while the locking end portion 9b of each locking spring 9 has a projection located opposite a recess 1c in the respective element 1. recess 1c and the corresponding locking portion 9b are slanted.

A set of biasing springs 11 is disposed on the lower side of carrier 7, each biasing spring 11 registering with a needle influencing element in a radial plane and having a curved end portion engaging a recess 1a in the correlated element 1. The inner ends of the biasing springs 11 are secured to carrier member 7 by the annular shielding plate 12.

The biasing spring means 11 provide the force P mentioned in connection with FIG. 1 which urges the element 1 to the illustrated outer operative positions in which the end portions 1b of the elements are respectively located under the butts 2a of the correlated cylinder needles 2. Each element 1 can be shifted to an inner position in which end portions 1b are spaced from butts 2a, and in this inoperative position, the locking portions 9b are located opposite recesses 1c, and biasing springs 11 are tensioned and store energy so that the respective element 1 tends to move from the inner inoperative position to the outer operative position. Each locking spring 9b has a locking position in which locking portion 9b is located in the recess 1c of the correlated element 1 and holds the same in the inoperative position, but each locking spring 9 can be moved to a releasing position illustrated in FIG. 5 in which the biasing spring 11 of the respective element 1 is free to shift the respective element 1 to the outer operative position. Locking springs 9 are tensioned in the illustrated releasing position and tend to move the locking position in which locking portion 9b is located in recess 1c.

A fixed annular member 13 is secured to the supporting axle 6 and covers the upper surface of rotary carrier means. Member 13 is formed with a peripheral cutout 14 in which electromagnetic means 15 is mounted which includes two outer continuously energized magnets 15a and 15c, and an electromagnetic selector means 15b whose core cooperates with the outer end portion of each locking spring 9 when the locking springs successively pass electromagnetic means 15b during rotation of the carrier means about axis X relative to the fixed member 13. Cutout 14 is closed by a member 14a, and a ring-shaped support 16 is secured to member 13 and member 14a by screws 16a and has an inner flange with two cams 17 and 18.

As best seen in FIGS. 5 and 6, cam 18 is located under the end portions of locking springs 9 and has a raised portion 18a before the selecting station S.S. where the electromagnetic means 15 is located. During rotation of the carrier means with locking springs 9, each locking spring, sliding along the raised portion 18a of cam 18 will be pressed to the tensioned releasing position illustrated in FIG. 5. The end of the cam track of cam portion 18a is located in a plane perpendicular to axis X and spaced such a distance from the lower surface of fixed member 13 and magnetic means 15a that each locking spring 9 is moved to a position sliding on the armature of magnetic means 15 when arriving at the selecting station. When during further turning movement of the carrier means, a locking spring 9 is moved beyond the

end of cam portion 18a it is still held by the magnetic means 15a, sliding on the same, until arriving at the electromagnetic selector means 15b which is energized and deenergized in accordance with a program. In the event that electromagnetic means 15b is energized, the respective locking spring 9 will slide on the armature of electromagnetic means 15 until arriving at magnetic means 15c, which is permanently energized, and holds such a locking spring 9 in the position 9" until the respective locking springs moves to a position located under a portion of fixed member 13 where it is released and assumes its normal lower position. If the respective correlated needle-influencing element 1 is in the outwardly advanced operative position, locking portion 9b cannot snap into recess 1c, but will abut the upper edge of the respective needle-influencing element 1. However, if the respective needle-influencing element 1 is in the inner inoperative position, locking portion 9b will fall into recess 1c and lock the respective needle-influencing element in the retracted inoperative position.

As best seen in FIG. 7, cam 17 has a raised inwardly projecting portion preceding the selecting station S.S., and since during rotation of the carrier means all needle-influencing elements 1 will engage cam 17 with shoulders of recesses 1d, all elements 1 are moved inwardly to the retracted inoperative position before arriving at the selecting station S.S.

Since a locking spring 9' which moved onto the lower surface of electromagnetic selector means 15b when the same was de-energized, resiliently moves to the lower position, it must fall into recess 1c of the correlated needle-influencing element 1, since all elements 1 are retracted to the inner inoperative position in which recess 1c registers with the locking projection 9b of the respective locking spring.

Cam 17 has a slanted end face 17a so that each needle-influencing element 1" which was not locked in the inoperative position by a locking spring in the position 9' is free to rapidly move in outward direction under the action of the respective biasing spring 11 which was tensioned when the respective needle-influencing element 1 was inwardly pushed by cam 17 in the region before the selecting station S.S. where the electromagnetic selector means 15b is located.

The carrier means of the pattern wheel turns further beyond the selecting station with elements 1 arranged in operative and inoperative positions in accordance with the predetermined pattern. The thus arranged elements 1 move along a plane slanted to the direction the cylinder needles 2, as best seen in FIG. 1a, and, consequently, the operative needle elements 1 raise the respective correlated needles to the knit position. Elements 1 locked in the retracted inoperative position by the respective locking springs 9 at the selecting station, are located too far inward to engage butts 2a, and consequently cannot raise the needles, which may be operated by a cam in the cam cylinder of the machine to rise to the tuck position.

Selected locking springs 9" in operative positions will be released by magnetic means 15c after further turning movement and will assume a position in which locking portion 9b abuts the upper edge of the correlated element 1. Locking springs 9 of needle-influencing elements in operative position will remain in this position until the respective element 1 has turned with the carrier means almost one revolution and is again engaged by cam 17 and pressed to the retracted inoperative position so that locking portion 9b can snap into the recess 1c before arriving at the selecting station.

The electromagnetic selector means 15b is energized by command impulses received from a program means which is controlled by a tape or by a Jacquard device. The speed of the tape, and the spacing of the control marks on the tape or card are selected in such a manner that a command signal can be given, or not given, whenever a needle influencing element 1 and the correlated locking spring 9

passes the selecting station with electromagnetic selector means 15b. This arrangement is known and corresponds to the manner in which the electromagnetic selector means of the U.S. Patent 3,079,775 is controlled. However, 5 while in the arrangement of the patent, the force of the electromagnetic selector means is used for shifting the needle-influencing elements, in the present invention the force for shifting the needle-influencing element is provided by biasing spring means 11, and the force for returning the elements to the inner inoperative position is provided by cam 18, while the electromagnetic means are used for controlling locking springs 9. FIGS. 5 to 7 disclose an arrangement in which biasing springs 11 shift selected needle-influencing elements 1 all the way to the 10 operative position, but it is possible to modify the arrangement by permitting the biasing springs to shift the needle-influencing elements only to an intermediate position where selected elements 1 are engaged by a cam which gradually moves selected elements outward to the 15 operative position, similar to the arrangement which will 20 now be described with reference to FIGS. 8 and 9.

In the embodiment of FIGS. 8 and 9, which is schematically illustrated in FIG. 3, the carrier means for needle-influencing elements 1i forms part of needle cylinder 3' 25 which has axially extending peripherally spaced grooves 3'a in which cylinder needles 2 are mounted for axial movement. A cam cylinder 230 carries inner stationary cams 130 and 121 cooperating with butts 2' of needles 2 and located at a higher level, and cams 122 and 120 co-operating with projections or butts 1" of needle-influencing 30 elements 1i and located at a lower level. It will be understood that the cams extend substantially around the inner surface of the cam cylinder 230, and that the butts of the needles and the needle-influencing elements move 35 along the cams during the rotation of needle cylinder 3'.

Since elements 1i are located in the same axially extending grooves as cylinder needles 2, they can directly cooperate with the same to shift the cylinder needles in axial direction to a knit position. Section 8A shows an 40 element 1i in an inoperative position, while being urged by a biasing spring 111 to move upwards toward the foot end 2" of the correlated needle 2 whose butt 2' rests on cam 130, as also shown at A in FIG. 9. Each element 1i' cooperates with a locking spring 109 whose lower end 45 is fixed to the carrier portion of the needle cylinder by a ring-shaped member 131. The upper locking portion 109b of each locking spring 109, abuts one edge of the correlated element 1i while being resiliently tensioned. Consequently, when a needle-influencing element 1i moves 50 under the action of its biasing spring 111 to an intermediate position shown in section 8B of FIG. 8, locking projection 109b can snap into recess 1ic. In this locked position, the upper end of element 1i is spaced from the foot 2" of needle 2 whose butt 2' rides on cam 130. In 55 the position shown in section 8C, the respective biasing spring 111 has moved a selected element 1i, which is not locked, to a higher position in which its upper end abuts the foot 2" of a needle 2. In the next following position shown in section 8D, cam 120 has moved element 1i to an 60 even higher operative position, and since element 1i engages needle 2, needle 2 is shifted simultaneously to the knit position while its butt engages the lower face of stitch cam 121 which, as best seen in FIG. 9 lowers the needle until the same slides again on cam 130 in the lower cast off position. At the same time, as shown in section 8E and 65 in FIG. 9 at E, a return cam portion 122a of cam 122 engages projection 1i' of element 1i to move the same downwardly to a retracted inoperative position, and since cam 122a merges into cam 122 which extends around the entire circumference of the cam cylinder, all needle-influencing elements 1i will arrive at A in FIG. 9 in the 70 position shown in section 8A.

Region B of FIG. 9 corresponding to section 8B, is a selecting station where an electromagnetic means 115 is provided. Electromagnetic means 115 includes two con-

tinuously energized magnetic means 115a and 115c, and an electromagnetic selector means 115b having an armature cooperating with locking portion 109b of each locking spring 109 which passes electromagnetic selector means 115b at a selecting station. While only one selecting station is illustrated in FIG. 9, it will be understood that several selecting stations may be provided around the circumference of the needle cylinder, each selecting station being provided on a knitting station of the circular knitting machine. The configuration of cams 122, 122a, 130 and 121 will correspond at each knitting station and selecting station to the configuration shown in FIG. 9.

Cam 122 extends around the inner surface of the cam cylinder in a plane perpendicular to the axis of the needle cylinder 3, but in the region of the selecting station S.S., cam 122 has an upwardly slanted cam portion 122', followed by a gap 132 between cam portion 122' and a raising cam 120 which has a rising portion between points C and D in FIG. 9. Cam 120 terminates after point D and is followed by the return cam 122a at point E.

Cam 130 extends also in a plane perpendicular to the axis of the needle cylinder to point C and has between points C and D a rising cam portion 130a which is designed to raise a needle whose butt 2' slides thereon to the tuck position. Needles passing over the end of cam portion 130a will be engaged by the lower face of stitch cam 121 and guided to a position in which the butts thereof slidingly rest on the horizontal cam 130.

During rotation of the needle cylinder in a direction of the arrow in FIG. 9, the lower ends of needles returned by stitch cam 121 will push corresponding needle-influencing elements 1i in the regions between points D and E in FIG. 9 to a lower position so that the projections 1i' assume a lower position engaging the lower face of the slanted cam portion 122a so that all elements 1i are moved downwardly to the inoperative position shown in section 8A in FIG. 8. During such movement from the position shown in section 8E to the position shown in section 8A, the locking portion 109b of the respective locking spring 109 passes into the slanted recess 1ic of the respective element, but since the element moves downward, the slanted shoulders of recess 1ic press the locking portion 109b again out of the recess so that the locking portion rests on the outer edge of the respective element 1i in the position shown at A in FIG. 9, and in section 8A.

As will become apparent from the following description, non-selected elements 1i will reach return cam portion 122a in the locking position shown in section 8B in which locking portion 109b is located in the corresponding recess 1ic in a locking position, as shown in section 8B. The downward slanting cam portion 122a will push elements 1i in this position downwardly to the position shown in section 8A so that the slanted shoulders of the respective recess 1ic will also push the locking portion 109b out of the recess and to a position slidingly engaging the edge of the respective element 1, as shown in section 8A.

All needle-influencing elements 1i arrive in the region of the selecting station at point B in the position shown in section 8A, and since the biasing springs 111 are tensioned in this lower inoperative position of elements 1i, projections 1i' press against the lower cam face of cam 122, and all elements 1i move upward to an intermediate position while the projections 1i' slide along the short upwardly slanting cam portion 122'.

Magnetic means 115a is a permanent magnet which acts on all locking springs 109 to hold the same in the position shown in section 8A, or to bend locking spring 109 away from element 1i and to a position slidingly abutting magnet 115a. Immediately thereafter, the locking spring moves with the rotating needle cylinder to a position located opposite electromagnetic selector means 115b, and a selection is now made according to whether

5 electromagnetic means 115b is energized, or not energized from the program control device of the machine. Assuming that electromagnetic selector means 115b is energized, it will hold the respective locking spring 109 sliding thereon so that the respective needle-influencing element 1i is free to move upward when arriving at the gap 132, and such upward movement is caused by the expansion of the biasing spring 111.

10 Other needle-influencing elements, which are not selected, pass electromagnetic selector means 115b while the same is de-energized, and resiliently snap into the recess 1ic of the respective correlated element 1i and assume the position shown in section 8B.

15 The non-selected elements 1i remain in the locked condition shown in section 8B while the needle cylinder continues its rotation until projection 1i' is engaged by the downwardly slanting cam portion 122a, and the respective element 1i is pushed downward so that locking portion 109b is pressed out of recess 1ic to the position shown in section 8A. Section 8C to 8E do not show a non-selected element, but illustrate a selected element 1i, so that for a non-selected element 1i, the position shown in section 8A follows the position shown in section 8B.

20 As explained above, the locking spring 109 of a selected element 1i is held by the energized electromagnetic selector means 115b, so that a selected element 1i is moved by its biasing spring 111 in upward direction until its upper end engages the foot portion of the corresponding needle 2 while projection 1i' moves through gap 132. Even if the biasing spring 111 does not move the respective element 1i so high, projection 1i' is immediately engaged by the pointed end of cam 120 and moves along the upper surface of the same first in a horizontal plane and then along the rising cam portion between points C and D in FIG. 9 so that the needle-influencing element is gradually moved to the highest operative position by cam 120 as shown in sections 8C and 8D of FIG. 8. In the region D, the needle is in the knit position, and its butt 2' is engaged by the lower surface of the downwardly slanted stitch cam 121 so that the needle is lowered positively until butt 2' rests on the upper surface of the horizontal cam portion 130, remaining in this position until approaching the next selecting station. As explained above, locking portion 109b momentarily snaps into the corresponding recess 1ic during the downward movement of the previously selected element 1i, but is pushed out again by the slanted shoulders of the recess to assume the position shown in section 8A.

25 During the movement of a selected element 1i in gap 132 onto the pointed end of cam 120, its locking spring 109 is held by the permanent magnet 115c, and when the respective selected element is positively guided on cam 120, locking spring 109 passes with the rotating carrier beyond the permanent magnet 115c and drops with its locking portion 109b onto the edge of the selected element 1i, as shown in sections 8D and 8E.

30 One selecting station provided with electromagnetic means 115 is illustrated, and corresponding selecting stations are provided along the periphery of the needle cylinder, the number of the selected and knitting stations depending on the type of machine. Circular knitting machines for knitting hosiery will have fewer knitting stations requiring selection than very large machines having a great needle cylinder diameter. In machines of this type 600 selections per second are carried out, and consequently it is of particular importance that the force of springs used for moving selected needle-influencing elements toward the operative positions since it is difficult to obtain by electromagnetic means the required very rapid acceleration of the needle-influencing elements.

35 In the embodiment of FIGS. 2 and 10, the cylinder needles are not raised to the knit position due to the inclination of the pattern wheel axis to the axis of the needle cylinder, as described with reference to FIGS. 1,

1a and 5, but the needles are shifted in axial direction by needle-influencing elements 1h moving in axial direction while rotating with the rotary carrier means of a pattern wheel whose axis is parallel to the axis of the needle cylinder. Referring particularly to FIG. 10, support means include a stationary cylindrical member 213 which is secured to a stationary member 206 mounted on the frame of the knitting machine. Cylindrical member 213 defines an axis of rotation Z about which annular carrier means 207 rotate. Member 213 and the carrier means can be together removed from the cylindrical support 206 if it is desired to replace or repair the pattern wheel. Cylindrical member 213 has a cutout 213a in which electromagnetic means 215 are mounted. Electromagnetic means 215 include an electromagnetic selector means 215b, and two permanently magnetized electromagnetic means 215a arranged on opposite sides of electromagnetic selector means 215b in circumferential direction, substantially as described with reference to FIGS. 6 and 9. An annular member 216 is secured to cylinder member 213, and has two cams 217 and 218 performing the functions of cams 17 and 18 described with reference to FIG. 5. Cams 217 and 218 are located in horizontal planes extending perpendicularly to the axis Z of the rotary carrier means 207, cam 217 having a downwardly slanting cam portion ending in the region of the selecting station represented by electromagnetic selector means 215 corresponding to the shape of cam 17, 17a in FIG. 7, and cam 218 has an inwardly rising radial cam portion terminating in a circular cam track concentric with axis C so that the shape of cam 218 corresponds to the shape of cam 18 shown in FIG. 6, cam 218 ending corresponding to the end 18a of cam 18, in the region of one of the magnetic means 215a before the selecting station represented by electromagnetic selector means 15b.

Carrier 207 and its outer annular portion 207a are connected by a circular shield plate 212 secured by screws 212a to the carrier means, and clamping a set of biasing spring 211 whose curved upper ends engage, respectively, recesses in correlated needle-influencing elements 1h. The needle-influencing elements are mounted in axially extending grooves of carrier means 207, 207a for movement in axial direction between a lower inoperative position in which the respective biasing spring 211 is tensioned, and the higher operative position in which its horizontal projection 1h' engages butt 2g of the correlated cylinder needle 2 from below to shift the same upward to the knit position. When any needle-influencing element 1h is in the lower inoperative position, not shown, the respective biasing spring 211 is tensioned and stores energy which is released when the respective needle-influencing element 1h is moved upward to the operative position.

Annular members 210 and 210a clamp the lower portions of locking springs 209 to carrier 207 so that locking springs 209 rotate with the needle-influencing elements 1h in positions registering with the same in radial planes passing through the axis Z. In the illustrated position of element 1h, the locking portion 209b is located opposite the edge of element 1h, but in the lower inoperative position of element 1h, locking portion 209b is located opposite recess 201c and can snap into the same to lock the respective correlated element 1h in the inoperative position.

As long as cam 218 engages the end portion of a locking spring 209, the same is held in the releasing position shown in FIG. 10 and cannot move to a position engaging the correlated element 1h.

A gear portion 207b on carrier 207 meshes with a corresponding gear portion 3b on needle cylinder 3 so that the carrier, the needle-influencing elements 1h, the locking springs 209, and biasing springs 211 rotate in synchronism with the needle cylinder in such a manner that the horizontal projections 1h' and the butts 2g of needles 2 are located in a common plane passing through 75

the axes of the pattern wheel and of the needle cylinder. The angular spacing between elements 1h is the same as the angular spacing of needles 2 of the needle cylinder so that successive needles and needle-influencing elements 5 assume the position shown in FIG. 10 for the common axial plane, and the electromagnetic selecting means 215b are located in the same plane.

During rotation of the needle cylinder and carrier means, the locking springs 209 approaching the selecting station are pressed inwardly by cam 218 so that each locking spring is in the releasing position shown in FIG. 10 and first slides along the core of the permanently magnetic means 215a and is held by the same after passing beyond the end of the raised cam portion 218, similar as explained with reference to FIG. 6. The turning carrier moves the thus held locking springs 209 onto the electromagnetic selector means 15b which are energized and de-energized in accordance with a predetermined pattern by pattern control means responding to a control tape or card. Assuming that electromagnetic selector means 213b is energized when a locking spring slides thereon in circumferential direction, the locking spring is held in the releasing position when the respective needle-influencing element 1h passes through the selecting station.

While approaching the selecting station, each needle-influencing element, and more particularly a shoulder of a recess therein, is engaged by cam 217 whose downwardly projecting cam portion presses all elements 1h to the lower inoperative position while tensioning the respective biasing springs 211. The shape of cam 217 corresponds to the shape of cam 17 shown in FIG. 7, and cam 217 terminates in the region of the selecting station, but behind electromagnetic selecting means 215b so that selected elements 1h whose locking springs 209 are held by electromagnetic selector means 215b in the releasing position shown in FIG. 10, move rapidly upward to the operative position when released by the free end of cam 217, and during such upward movement, the horizontal projection 1h' engaging butt 2g of the correlated needle 2, raises needle 2 to the knit position.

However, if electromagnetic selector means 215b is not energized when a non-selected element 1h passes the selecting station, then the corresponding locking means 209 passing from the leading permanent magnet 215a onto electromagnetic selector means 215b, is not held by the same and moves due to its resilient tension to a locking position in which locking portion 209b projects into the recess 201c of the correlated element 1h and locks the same in the inoperative position while the same is still held in this position by the projecting cam portion of cam 217. Of course, element 1h thus locked by the locking spring 209 cannot move upward when passing with the rotating carrier beyond the end of cam 217, but remain locked in the inoperative position while travelling with the rotating carrier one revolution until again arriving in the region of cam 218 which operates all locking springs 209 to at least temporarily release the corresponding elements 1h.

The selected elements 1h which are in the operative position when passing beyond the selecting station are pushed back in the inoperative position by cam 217 before arriving at the selecting station. Locking springs 209 of selected elements 2h slide first along electromagnetic selector means 215b, and then along the permanent magnet 215a on the other side of electromagnetic means 215b and corresponding to the permanent magnet 15c in FIG. 6. After a locking spring 209 has been turned by the rotating carrier beyond the second permanent magnet, it is released and moves due to its resilient tension toward the corresponding element 1h, but since the same is in the higher operative position, locking portion 209b abuts the edge of the element in the region below recess 201c. When cam 217 moves the respective element 1h back to the lower inoperative position, recess 201c is moved to a position in which lock-

ing portion 209b can snap into the same, if locking spring 209 is not held by electromagnetic selector means 215b. In the embodiment illustrated in FIG. 10, the force of the released biasing spring 211 is used for shifting the respective selected element 1h, and for raising the corresponding selected needle 2 to the knit position. However, similar to the embodiment shown in FIGS. 8 and 9, a cam corresponding to cam 120 may be provided following the selecting station, and positioned in relation to cam 217 as is cam 120 to cam 122 and 122' in FIG. 9, so that the force of the biasing 211 is used for moving the selected element 1h through a gap whereupon the further movement of the selected element is accomplished by a rising cam, corresponding to cam 120, whereby the force for raising the needle is not provided by biasing spring 211, but by the drive means which rotate the pattern wheel with the needle-influencing elements since the needle-influencing elements are forced to travel upward along the above-mentioned cam along which they are carried by the rotary driven carrier of the pattern wheel.

As noted above, the energizing and de-energizing of electromagnetic selector means is carried out in all embodiments of the invention by program controlled means which sense Jacquard cards or program tapes, preferably film tapes. Due to the high speed of operation, which may be 600 impulses and selection per second, electronic control of the electromagnetic selector means is preferred, and, for example, a film tape, driven from the needle cylinder, may have control marks in the form of small transparent rectangles forming a plurality of program tracks respectively sensed by sensing means associated with the several knitting stations and corresponding electromagnetic selector means. The sensing means preferably include an optical sensing system including a source of light projecting a beam toward the respective sensed track, and a photocell producing an impulse when light passes through a transparent mark of the respective program track. Any electric impulse is amplified in a transistor amplifier, and supplied to the electromagnetic selector means at the respective knitting and selection station. This arrangement is not an object of the invention, and consequently not illustrated.

In the embodiment of FIGS. 2 and 10, the needle cylinder rotates about an axis Y—Y, and the pattern wheel rotates about an axis Z—Z parallel to the axis of the needle cylinder so that the axially moving needle-influencing elements 1h can directly shift the cylinder needles to the desired knit position.

In the embodiment of FIGS. 3, 8 and 9, the needle-influencing elements 1i are not mounted in a pattern wheel, but in an annular carrier which rotates about the axis Y—Y so that the needle-influencing elements 1i can be disposed in the same axial grooves as the cylinder needles 2 for directly shifting the same.

In the same manner as the cylinder needles are shifted in the embodiments of FIGS. 2 and 3, selected dial needles can be shifted in accordance with a predetermined pattern, and such an arrangement is schematically illustrated in FIG. 4. The dial 4 rotates about the axis Y—Y in synchronism with the needle cylinder 3, and has radial grooves in which the dial needles 5 are mounted for radial movement between inner and outer positions. Needle-influencing elements 1K are movable in radial grooves of a rotary carrier, and at a selecting station through which every needle-influencing element 1K passes, a selection is made so that the needle-influencing elements 1K of selected dial needles 5 move in radial direction to engage the butt of the respective dial needle 5 and to shift the same outwardly. FIG. 4 schematically illustrates by arrow P the force of the biasing springs described with reference to the other embodiments.

If the principle of the embodiments of FIGS. 2 and 10 is applied, at least one pattern wheel is provided with a carrier rotatable about an axis parallel to the axis Y—Y, but the construction of FIG. 5 is used. The

needle-influencing elements are mounted in radial grooves of a rotary carrier, associated with locking springs, controlled by cams, and held by the locking springs in the inoperative inner position unless released under control of electromagnetic selecting means to move in radial direction under the action of the biasing spring thereof. Each selected needle-influencing element moves in radial direction in the radial plane of the selecting station, and shifts the corresponding needle 5 outwardly by engaging its butt.

If the principle of FIG. 3 is applied, a ring-shaped carrier is secured to the dial 4 and rotates about the axis Y—Y in synchronism with the same. However, a construction corresponding to FIG. 5 is used for moving selected needle-influencing elements in radial direction when passing at a selecting station through a radial plane, so that selected elements engage the butts of the corresponding dial needles 5 and shift the same outwardly. These constructions are not illustrated in detail, since those skilled in the art will know how to adapt the construction of FIG. 5 for the purpose of operating the dial needles by direct radial shifting by selected needle-influencing elements which are urged outwardly by biasing springs, and are unlocked at the selecting station to shift the corresponding dial needles.

It will be understood that each of the elements described above, or two or more together, may also find a useful application in other types of pattern control arrangement differing from the types described above.

While the invention has been illustrated and described as embodied in a pattern control arrangement including needle-influencing elements in which energy is stored which is released at a selecting station to move selected elements to an operative position, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention, and, therefore, such adaptations should and are intended to be comprehended within the meaning and range of equivalence of the following claims.

What is claimed as new and desired to be secured by Letters Patent is:

1. A pattern control arrangement for a knitting machine, comprising, in combination, carrier means mounted for rotation; a set of needle-influencing elements supported on said carrier means for rotation therewith past at least one selecting station and for movement thereon between an inoperative position and an operative position adapted to cause displacement of a correlated needle; biasing means for biasing said needle-influencing elements to move toward said operative position; means for moving said needle-influencing elements before said selecting station to said inoperative position; locking means mounted on said carrier means movable between a locking position for locking non-selected needle-influencing elements in said inoperative position, and a releasing position releasing selected needle-influencing elements for movement toward said operative position; and control means located at said selecting station for moving said locking means between said releasing and locking positions in accordance with a predetermined program.

2. A pattern control arrangement for a knitting machine, comprising, in combination, support means; carrier means mounted on said support means for rotation; a set of needle-influencing elements supported on said carrier means for rotation therewith past at least one selecting station and for movement thereon between an inoperative position and an operative position adapted to cause displacement of a correlated needle; biasing means disposed

on said carrier means and biasing said needle-influencing elements to move toward said operative position; means for moving said needle-influencing elements before said selecting station to said inoperative position; a set of locking means mounted on said carrier means in positions registering with said needle-influencing elements, respectively, each locking means being movable between a locking position for locking the respective needle-influencing element in said inoperative position, and a releasing position releasing the respective needle-influencing element for movement toward said operative position; and control means located at said selecting station for moving said locking means individually between said releasing and locking positions in accordance with a predetermined program.

3. A pattern control arrangement for a knitting machine, comprising, in combination, carrier means mounted for rotation; a set of needle-influencing elements supported on said carrier means for rotation therewith past at least one selecting station and for movement thereon between an inoperative position and an operative position adapted to cause displacement of a correlated needle; biasing means for biasing said needle-influencing elements to move toward said operative position; means for moving said needle-influencing elements before said selecting station to said inoperative position; locking means mounted on said carrier means movable between a locking position for locking non-selected needle-influencing elements in said inoperative position, and a releasing position releasing selected needle-influencing elements for movement toward said operative position; and control means including electromagnetic selector means located at said selecting station for moving said locking means between said releasing and locking positions, said electromagnetic selector means being adapted to be energized and deenergized in accordance with a predetermined program.

4. A pattern control arrangement for a knitting machine, comprising, in combination, support means; carrier means mounted on said support means for rotation; a set of needle-influencing elements supported on said carrier means for rotation therewith past at least one selecting station and for movement thereon between an inoperative position and an operative position adapted to cause displacement of a correlated needle; biasing means disposed on said carrier means and biasing said needle-influencing elements to move toward said operative position; means for moving said needle-influencing elements before said selecting station to said inoperative position; a set of locking means mounted on said carrier means in positions registering with said needle-influencing elements, respectively, each locking means being movable between a locking position for locking the respective needle-influencing element in said inoperative position, and a releasing position releasing the respective needle-influencing element for movement toward said operative position; and control means including electromagnetic selector means located at said selecting station for moving said locking means individually between said releasing and locking positions, said electromagnetic selector means being adapted to be energized and deenergized in accordance with a predetermined program.

5. A pattern control arrangement for a knitting machine, comprising, in combination, support means; carrier means mounted on said support means for rotation; a set of needle-influencing elements supported on said carrier means for rotation therewith past at least one selecting station and for movement thereon between an inoperative position and an operative position adapted to cause displacement of a correlated needle; a set of biasing spring means secured to said carrier means in positions registering with said needle-influencing elements and respectively individually biasing said needle-influencing elements to move toward said operative position; stationary cam means disposed on said support means for moving said needle-influencing elements before said selecting station

to said inoperative position; a set of locking means mounted on said carrier means in positions registering with said needle-influencing elements, respectively, each locking means being movable between a locking position for locking the respective needle-influencing element in said inoperative position, and a releasing position releasing the respective needle-influencing element for movement toward said operative position; and control means located at said selecting station for moving said locking means individually between said releasing and locking positions in accordance with a predetermined program.

6. A pattern control arrangement for a knitting machine, comprising, in combination, support means; carrier means mounted on said support means for rotation; a set of needle-influencing elements supported on said carrier means for rotation therewith past at least one selecting station and for movement thereon between an inoperative position and an operative position adapted to cause displacement of a correlated needle; biasing means disposed on said carrier means and biasing said needle-influencing elements to move toward said operative position; means for moving said needle-influencing elements before said selecting station to said inoperative position; a set of locking spring means mounted on said carrier means in positions registering with said needle-influencing elements, respectively, each locking spring means being movable between a locking position for locking the respective needle-influencing element in said inoperative position, and a releasing position releasing the respective needle-influencing element for movement toward said operative position, said locking spring means being tensioned in one of said positions thereof and tending to assume the other position; and control means located at said selecting station for moving selected locking spring means individually to said one position so that non-selected locking spring means move to said other position thereof in accordance with a predetermined program.

7. A pattern control arrangement for a knitting machine, comprising, in combination, support means; carrier means mounted on said support means for rotation; a set of needle-influencing elements supported on said carrier means for rotation therewith past at least one selecting station and for movement thereon between an inoperative position and an operative position adapted to cause displacement of a correlated needle; biasing means disposed on said carrier means and biasing said needle-influencing elements to move toward said operative position; means for moving said needle-influencing elements before said selecting station to said inoperative position; a set of locking spring means mounted on said carrier means in positions registering with said needle-influencing elements, respectively, each locking spring means being movable between a locking position for locking the respective needle-influencing element in said inoperative position, and a tensioned releasing position releasing the respective needle-influencing element for movement toward said operative position, said locking spring means tending to assume said locking position; and control means located at said selecting station for moving selected locking spring means only to said releasing position so that non-selected locking spring means move to said locking position thereof in accordance with a predetermined program.

8. A pattern control arrangement for a knitting machine, comprising, in combination, support means; carrier means mounted on said support means for rotation; a set of needle-influencing elements supported on said carrier means for rotation therewith past at least one selecting station and for movement thereon between an inoperative position and an operative position adapted to cause displacement of a correlated needle; biasing means disposed on said carrier means and biasing said needle-influencing elements to move toward said operative position; means for moving said needle-influencing elements before said selecting station to said inoperative position; a set of lock-

ing spring means mounted on said carrier means in positions registering with said needle-influencing elements, respectively, each locking spring means being movable between a locking position for locking the respective needle-influencing element in said inoperative position, and a tensioned releasing position releasing the respective needle-influencing element for movement toward said operative position, said locking spring means tending to assume said locking position; and control means including cam means for moving each locking spring means successively to said releasing position before arriving at said selecting station, and electromagnetic means located at said selecting station for holding selected locking spring means only to said releasing position so that non-selected locking spring means move to said locking position thereof, said electromagnetic means being adapted to be energized and deenergized in accordance with a predetermined program.

9. A pattern control arrangement for a knitting machine, comprising, in combination, support means; carrier means mounted on said support means for rotation; a set of needle-influencing elements supported on said carrier means for rotation therewith past at least one selecting station and for movement thereon between an inoperative position and an operative position adapted to cause displacement of a correlated needle; a set of biasing spring means secured to said carrier means in positions registering with said needle-influencing elements and respectively individually biasing said needle-influencing elements to move toward said operative position; stationary cam means disposed on said support means for moving said needle-influencing elements before said selecting station to said inoperative position; a set of locking spring means mounted on said carrier means in positions registering with said needle-influencing elements, respectively, each locking spring means being movable between a locking position for locking the respective needle-influencing element in said inoperative position, and a tensioned releasing position releasing the respective needle-influencing element for movement toward said operative position, said locking spring means tending to assume said locking position; and control means including cam means for moving each locking spring means successively to said releasing position before arriving at said selecting station, and electromagnetic means located at said selecting station for holding selected locking spring means only to said releasing position so that non-selected locking spring means move to said locking position thereof, said electromagnetic means being adapted to be energized and deenergized in accordance with a predetermined program.

10. A pattern control arrangement for a knitting machine, comprising, in combination, support means; carrier means mounted on said support means for rotation; a set of needle-influencing elements supported on said carrier means for rotation therewith past at least one selecting station and for movement thereon between an inoperative position and an operative position adapted to cause displacement of a correlated needle; a set of biasing spring means secured to said carrier means in positions registering with said needle-influencing elements and respectively individually biasing said needle-influencing elements to move toward said operative position; stationary cam means disposed on said support means for moving said needle-influencing elements before said selecting station to said inoperative position; a set of locking spring means mounted on said carrier means in positions registering with said needle-influencing elements, respectively, each locking spring means being movable between a locking position for locking the respective needle-influencing element in said inoperative position, and a tensioned releasing position releasing the respective needle-influencing element for movement toward said operative position, said locking spring means tending to assume said locking position; and control means including cam means for moving each locking spring means successively to said

releasing position before arriving at said selecting station, and electromagnetic means located at said selecting station for holding selected locking spring means only to said releasing position so that non-selected locking spring means move to said locking position thereof, said electromagnetic means being adapted to be energized and deenergized in accordance with a predetermined program, said control means including two magnetic means disposed at said selecting station before and behind said electromagnetic means adjacent to the same for holding all said locking spring means and only said selected locking spring means in said releasing position.

11. A pattern wheel arrangement for a knitting machine having needles, comprising, in combination, support means including a fixed member; selector means mounted on said support means and being operable between a selecting condition and an inoperative condition; a carrier mounted on said support means for rotation; a set of needle-influencing elements supported on said carrier for rotation therewith past said selector means, and for movement on said carrier between an inoperative position and an operative position for displacing a correlated needle; biasing means for biasing said needle-influencing elements to move to said operative position; first cam means secured to said member for moving said elements to said inoperative position before passing said selector means and shaped to permit movement of said elements to said operative position in the region of said selector means; a set of locking springs mounted on said carrier in positions registering with said elements, respectively, each locking spring having a fixed end portion secured to said carrier end and a locking portion and having a normal locking position for locking the respective element by said locking portion, and a tensioned releasing position releasing the respective element for movement to said operative position; and second cam means secured to said member for moving said locking portions of said locking springs successively to said releasing position before arriving at said selector means during rotation of said carrier, said selector means holding in said selecting condition passing locking springs in said releasing position so as to permit movement of passing selected needle-influencing elements to said operative position, and permitting in said inoperative position passing locking springs to move to said locking position to lock non-selected elements in said inoperative position.

12. A pattern wheel arrangement for a knitting machine having needles rotatable about an axis, comprising, in combination, support means including a fixed member and mounted at a knitting station of the machine; electromagnetic selector means mounted on said support means and being operable between an energized selecting condition and a de-energized inoperative condition; a carrier mounted on said support means for rotation about an axis extending at an acute angle to said axis; a set of needle-influencing elements supported on said carrier for rotation therewith past said selector means, and for radial movement on said carrier between an inoperative position and an operative position for displacing a correlated needle while turning with said carrier; biasing means for biasing said needle-influencing elements to move to said operative position; first partly circular cam means secured to said member for moving said elements to said inoperative position before passing said selector means and shaped to permit movement of said elements to said operative position in the region of said selector means; a set of locking springs mounted on said carrier in positions registering with said elements, respectively, each locking spring having a fixed end portion secured to said carrier end and a locking portion and having a normal locking position for locking the respective element by said locking portion, and a tensioned releasing position releasing the respective element for movement to said operative position; and second partly circular cam means secured to said member for moving said locking portions

of said locking springs successively to said releasing position before arriving at said selector means during rotation of said carrier, said electromagnetic selector means holding in said selecting condition passing locking springs in said releasing position so as to permit movement of passing selected needle-influencing elements to said operative position, and permitting in said inoperative position passing locking springs to move to said locking position to lock non-selected elements in said inoperative position.

13. A pattern wheel arrangement for a knitting machine having needles rotatable about an axis, comprising, in combination, support means including a fixed plate and mounted at a knitting station of the machine; electromagnetic selector means mounted on said plate and being operable between an energized selecting condition and a de-energized inoperative condition; a carrier mounted on said support means for rotation about an axis extending at an acute angle to said axis; a set of needle-influencing elements supported on said carrier for rotation therewith past said selector means, and for radial movement on said carrier between an inoperative position and an operative position for displacing a correlated needle while turning with said carrier, said elements having recesses; a set of biasing spring means for biasing said needle-influencing elements to move to said operative position; first partly circular cam means secured to said plate located in said recesses for moving said elements to said inoperative position before passing said selector means and shaped to permit movement of said elements to said operative position in the region of said selector means; a set of locking springs mounted on said carrier in positions registering with said elements, respectively, each locking spring having a fixed end portion secured to said carrier end and a locking portion and having a normal locking position engaging other recesses of said recesses for locking the respective element by said locking portion, and a tensioned releasing position releasing the respective element for movement to said operative position; and second partly circular cam means secured to said plate for moving said locking portions of said locking springs successively to said releasing position before arriving at said selector means during rotation of said carrier, said electromagnetic selector means holding in said selecting condition passing locking springs in said releasing position so as to permit movement of passing selected needle-influencing elements to said operative position, and permitting in said inoperative position passing locking springs to move to said locking position to lock non-selected elements in said inoperative position.

14. A pattern wheel arrangement for a knitting machine having needles rotatable about an axis, comprising, in combination, support means including a fixed member and mounted at a knitting station of the machine; electromagnetic selector means mounted on said support means and being operable between an energized selecting condition and a de-energized inoperative condition; a carrier mounted on said support means for rotation about an axis extending parallel to said axis; a set of needle-influencing elements supported on said carrier for rotation therewith past said selector means, and for radial movement on said carrier between an inoperative position and operative position for displacing a correlated needle in axial direction; biasing means for biasing said needle-influencing elements to move to said operative position; first cam means secured to said member for moving said elements to said inoperative position before passing said selector means and shaped to permit movement of said elements to said operative position in the region of said selector means; a set of locking springs mounted on said carrier in positions registering with said elements, respectively, each locking spring having a fixed end portion secured to said carrier end and a locking portion and having a normal locking position for locking the respective element by said locking portion, and a tensioned releasing position

ing position releasing the respective element for movement to said operative position; and second cam means secured to said member for moving said locking portions of said locking springs successively to said releasing position

5 before arriving at said selector means during rotation of said carrier, said electromagnetic selector means holding in said selecting condition passing locking springs in said releasing position so as to permit movement of passing selected needle-influencing elements to said operative position, and permitting in said inoperative position passing locking springs to move to said locking position to lock non-selected elements in said inoperative position.

15. A pattern wheel arrangement for a knitting machine having a needle cylinder and cylinder needles rotatable about an axis, comprising in combination, support means including a fixed cylinder member having an axis parallel to said axis and mounted at a knitting station of the machine; electromagnetic selector means mounted

20 on said cylinder member and being operable between an energized selecting condition and a de-energized inoperative condition; a carrier of annular shape surrounding said cylindrical member and mounted on said support means for rotation, said selector means being located in

25 a plane passing through said axes; a set of needle-influencing elements supported on said carrier for rotation therewith past said selector means, and for parallel movement on said carrier between an inoperative position and an operative position for displacing a correlated needle,

30 said elements having recesses, and radial projections outwardly projecting beyond said carrier for cooperation with the needles; biasing means for biasing said needle-influencing elements to move to said operative position; first cam means secured to said cylindrical member located in said recesses for moving said elements to said inoperative position before passing said selector means and shaped to permit movement of said elements to said operative position in the region of said selector means; a set of locking springs mounted on said carrier in positions

35 registering with said elements, respectively, each locking spring having a fixed end portion secured to said carrier end and a locking portion and having a normal locking position engaging other recesses of said recesses for locking the respective element by said locking portion, and a tensioned releasing position releasing the respective element for movement to said operative position; and second cam means secured to said cylindrical member for moving said locking portion of said locking springs successively to said releasing position before arriving at

40 said selector means during rotation of said carrier, said electromagnetic means holding in said selecting condition passing locking springs in said releasing position so as to permit movement of passing selected needle-influencing elements to said operative position, and permitting in said

45 inoperative position passing locking springs to move to said locking position to lock non-selected elements in said inoperative position.

16. In a circular knitting machine, in combination, support means including a cam cylinder; selector means mounted on said cam cylinder at at least one knitting station and being operable between a selecting condition and an inoperative condition; a needle cylinder mounted on said support means for rotation and having axially extending grooves; needles guided in said grooves for axial movement

65 and for rotation with said needle cylinder; a set of needle-influencing elements mounted in said grooves for rotation with said needle cylinder, and for axial movement between an inoperative position and an operative position for shifting the correlated needle in the respective groove; biasing means for biasing said needle-influencing elements

70 to move to said operative position; cam means secured to said cam cylinder for moving said elements to said inoperative position before passing said selector means and shaped to permit movement of said elements to said operative position in the region of said selector means; a set of

locking springs mounted on said carrier in positions registering with said elements, respectively, each locking spring having a fixed end portion secured to said carrier end and a locking portion and having a normal locking position for locking the respective element by said locking portion, and a tensioned releasing position releasing the respective element for movement to said operative position; and said selector means moving and holding in said selecting condition passing locking springs in said releasing position so as to permit movement of passing selected needle-influencing elements to said operative position, and permitting in said inoperative position passing locking springs to move to said locking position to lock non-selected elements in said inoperative position.

17. In a circular knitting machine, in combination, support means including a cam cylinder; selector means mounted on said cam cylinder at at least one knitting station and being operable between a selecting condition and an inoperative condition; a needle cylinder mounted on said support means for rotation and having axially extending grooves; needles guided in said grooves for axial movement and for rotation with said needle cylinder; a set of needle-influencing elements mounted in said grooves for rotation with said needle cylinder, and for axial movement between an inoperative position and an operative position for shifting the correlated needle in the respective groove; biasing means for biasing said needle-influencing elements to move to said operative position; cam means secured to said cam cylinder for moving said elements to said inoperative position before passing said selector means and shaped to permit movement of said elements to an intermediate position in the region of said selector means so that an element in said intermediate position abuts a correlated needle; other cam means secured to said cam cylinder following said region and shaped to move said elements from said intermediate position to an operative position for shifting the correlated needles to a knit position; a set of locking springs mounted on said carrier in positions registering with said elements, respectively, each locking spring having a fixed end portion secured to said carrier end and a locking portion and having a normal locking position for locking the respective element by said locking portion, and a tensioned releasing position releasing the respective element for movement to said operative position; and said selector means moving and holding in said selecting condition passing locking springs in said releasing position so as to permit movement of passing selected needle-influencing elements to said operative position, and permitting in said inoperative position passing locking springs to move to said locking position to lock non-selected elements in said inoperative position.

18. In a circular knitting machine, in combination, support means including a cam cylinder; electromagnetic means mounted on said cam cylinder at at least one knitting station and being operable between an energized condition and an inoperative condition; a needle cylinder mounted on said support means for rotation and having axially extending grooves; needles guided in said grooves for axial movement and for rotation with said needle cylinder; a set of needle-influencing elements mounted in said grooves for rotation with said needle cylinder, and for axial movement between an inoperative position and an operative position for shifting the correlated needle in the respective groove; a set of biasing spring means for biasing said needle-influencing elements to move to said operative position; cam means secured to said cam cylinder for moving said elements to said inoperative position before passing said selector means and shaped to permit movement of said elements to an intermediate position in

the region of said selector means so that an element in said intermediate position abuts a correlated needle; other cam means secured to said cam cylinder following said region and shaped to move said elements from said intermediate position to an operative position for shifting the correlated needles to a knit position; a set of locking springs mounted on said carrier in positions registering with said elements, respectively, each locking spring having a fixed end portion secured to said carrier end and a locking portion and having a normal locking position for locking the respective element by said locking portion, and a tensioned releasing position releasing the respective element for movement to said operative position; and said selector means moving and holding in said selecting condition passing locking springs in said releasing position so as to permit movement of passing selected needle-influencing elements to said operative position, and permitting in said inoperative position passing locking springs to move to said locking position to lock non-selected elements in said inoperative position.

19. A machine as set forth in claim 18 and including two magnetic means located before and behind said electromagnetic means in the direction of rotation of said carrier adjacent the same and being continuously energized.

20. A pattern wheel arrangement for a knitting machine having a dial with dial needles rotatable about an axis, comprising, in combination, support means including a fixed member; selector means mounted on said support means and being operable between a selecting condition and an inoperative condition; a carrier mounted on said support means for rotation about an axis extending in the direction of said axis; a set of needle-influencing elements supported on said carrier for rotation therewith past said selector means, and for radial movement on said carrier between an inoperative position and an operative position for displacing a correlated needle; biasing means for biasing said needle-influencing elements to move to said operative position; first cam means secured to said member for moving said elements to said inoperative position
